UNITED STATES PATENT OFFICE

141,433

DESIGN FOR A LUMINOUS LIGHT SWITCH SHIELD

James Ross, Hubbard Woods, Ill.

Application February 1, 1945, Serial No. 117,708

Term of patent 14 years

(Cl. D26—13)

To all whom it may concern:

Be it known that I, James Ross, a citizen of the United States, residing at Hubbard Woods in the county of Cook and State of Illinois, have invented a new, original, and ornamental Design for a Luminous Light Switch Shield, of which the following is a specification, reference being had to the accompanying drawing forming a part thereof:

Fig. I shows a face view of the luminous light switch shield embodying my design.

Fig. II is a cross-section on the line 2—2 of Figure I.

I claim:

The ornamental design for a luminous light switch shield, substantially as shown.

JAMES ROSS.
